UNITED STATES PATENT OFFICE.

OTTO FRANKE, OF BIRMINGHAM, ALABAMA, ASSIGNOR TO BIRMINGHAM MACHINE & FOUNDRY CO., A CORPORATION OF ALABAMA.

INTERMEDIATE CARRIER FOR SUGAR MILLS.

Application filed April 25, 1925. Serial No. 25,948.

My invention relates to improvements in cane sugar mills, and is more particularly concerned with the improvement of the intermediate cane chute which serves to transfer 5 or convey the bagasse from one mill to another.

More particularly, my invention relates to an intermediate cane chute or carrier of the type in which all moving parts are eliminated and the rolls of one mill act to deliver 10 the bagasse in a sheet or blanket of substantially constant thickness automatically and uniformly to the rolls of the succeeding mill. In intermediate carriers of the type in question 15 serious difficulty has arisen by reason of the tendency of the bagasse to choke in the chute at the intake end of the carrier, and when this occurs the rolls feeding the bagasse to the intermediate carrier will become 20 jammed, the walls of the chute will tend to become distorted, and the throat of the chute will be filled with bagasse which is so tightly packed as to be very difficult to remove and which while being removed necessitates a 25 shutting down of the mill.

I have discovered that this tendency of the bagasse to pack in the chute at the intake end of the intermediate carrier, and thus to choke the carrier, can be avoided if the intake chute 30 is provided with a yieldable wall adapted to give automatically so as to expand the cross sectional area of the chute and prevent any tendency of the bagasse to choke therein, leaving it at all times free to pass up onto the 35 open part of the carrier in a sheet of substantially uniform thickness.

More particularly my invention contemplates providing the carrier at its intake end with a relatively short chute having a hinged 40 wall, preferably its upper wall, and having the free end of said wall which is remote from the rolls feeding the bagasse to the carrier, automatically controlled as to position by a yieldable means which can be set so that under 45 excessive pressures upwardly from the bagasse the hinged wall will be permitted to give and thus release the bagasse so that it will not choke.

My invention also embodies the details of 50 construction and arrangement of parts which

in their preferred embodiment only are illustrated in the accompanying drawings which form a part of this specification, and in which:—

Fig. 1 is a cross-sectional view of two 55 spaced cane sugar mills and their intermediate carrier constructed in accordance with my invention.

Fig. 2 is an enlarged detail view of the 60 intake chute of the carrier shown in cross-section.

Fig. 3 is a side view of the intake chute and part of the mill on which it is mounted.

Fig. 4 is a partial plan view of the intake 65 chute of the carrier.

Similar reference numerals refer to similar parts throughout the drawings.

In the embodiment of my invention illustrated, I show my improved type of carrier associated with the discharge side of the rolls 1 and 2 of the initial mill 3, and acting to deliver the stream or blanket of bagasse to the intake side of the rolls 4 and 5 of the succeeding mill 6. The carrier itself comprises a chute with a gradually sloping intake end 7 75 and a more sharply sloping and relatively shorter discharge end 8. The chute has side walls 9 which extend from scraper bars 10 and 11, which are disposed respectively above and below the intake chute 12 on the mill 2, to the mill 6. The chute is provided with an upper scraper toe 13 shaped and mounted to engage the roll 1, and with a bottom scraper toe 14 which engages the lower roll 2. It will be observed that the toe 13 has a top wall 15 of the chute mounted flush in its recessed end portion 16 and that it has mounted between this top wall 15 and a retainer plate 17 the cylindrical or hinge end 18 of a yieldable top 80 presser plate 19. This plate 19 has mounted in the upper side thereof a stud screw 20 which projects through a slot in the top wall 15 of the chute and there receives a taper washer 21 held in position by lock nuts 22. This serves as a means to limit the downward 85 swing of the presser plate 19 into the chute 12. Near its free end the presser plate is engaged by yieldable means such as the plungers 23, each having its head disposed to reciprocate in a spring barrel 24 in which 90

95

95

95

100

is disposed a coil spring 25 seated at one end on the head of the plunger 23 and at the other end engaging the head 26 on an adjustable screw 27 threaded through the cap 28 of the barrel. The barrels are mounted on the top wall 15 of the chute by brackets 29 with the plungers passing through suitable openings in said top wall 15 and acting to hold the presser plate yieldably depressed into the chute to the limit permitted by the adjustment of the nuts 22 on the stud bolt 20.

In operation, as the stream of bagasse is discharged from the rolls 1 and 2 and collected by the toes 13 and 14, it passes in a stream into the chute 12 and is normally forced by the feed of the rolls 1 and 2 to rise up the inclined portion 7 of the carrier and to fall by gravity down its discharge end 8 to the succeeding mill. The yieldable presser plate 19 is set to give the desired thickness to the bagasse stream or blanket. Whenever, for any reason the bagasse tends to choke in the intake chute 12 of the carrier, the pressure of the dense mass as it becomes compressed in the intake chute will overcome the resistance of springs 25, causing the presser plate to give and swing upwardly about its hinge end 18, thus relieving the congestion of the bagasse in the intake chute and permitting the feed to continue without interruption and with a substantially uniform depth of stream which gives a substantially constant delivery of the bagasse to the succeeding mill.

While it is to be understood my improved yieldable pressure plate may be associated with any standard type of carrier or intake chute therefor, I have shown it in the accompanying drawings associated with an intake chute having bagasse side plates 30 connected by plates 31 to the sides 9 of the chute and having top and bottom brackets 32 and 33 in which the scraper bars 10 and 11, respectively, are mounted. The scraper bars have their ends which are mounted in said plates rounded, and I key to said ends the arms 34 and 35, which at their free ends on each side of the chute are connected by a bolt 36 which projects above the upper arms of each pair and has a coiled spring 37 surrounding it and bearing at one end on the upper arm and at the other end on a seat 38 held adjustable on the bolt by a nut 39. These act as yieldable means to rock the scraper bars and force the scraper toes 13 and 14 against the rolls. Each side plate has a bracket 40 which is bolted to the adjacent housing 41 of the mill 3. It is, as stated, to be understood that assembly of parts as thus described in detail for the intake chute do not form a particular part of my invention but serve to illustrate a typical intake chute structure with which my invention has been successfully used.

My invention contemplates broadly the utilization of any yieldable wall so placed at

the intake end of the intermediate carrier that, by yielding outwardly, it will prevent the bagasse choking the chute as it is discharged from the feed rolls of the primary mill.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

What I claim is:

1. An intermediate carrier for spaced sugar mills having rolls, comprising a chute having side walls and upwardly and downwardly inclined portions, shoes mounted at the intake end of said chute and co-acting with the feed rolls, the upper shoe having a pivotal support, a presser plate hingedly mounted below the plane of said support, adjustable screw means to limit the downward swinging movement of the plate, and a spring-pressed plunger acting on the free end of said plate to press it yieldably against the bagasse being fed to the rising intake end of said chute.

2. An intermediate carrier for spaced sugar mills having rolls, comprising a chute having side walls and upwardly and downwardly inclined portions, shoes mounted at the intake end of said chute and co-acting with the rolls of the first mill, the upper shoe having a pivotal support, a presser plate hingedly mounted between the line of said support and the first mill, and a spring-pressed plunger acting upon the free end of said plate to press it yieldingly against the bagasse being fed to the rising intake end of said chute.

3. A chute for transferring bagasse between side walls and an upwardly-inclined bottom at its receiving end and a downwardly-inclined bottom at its delivery end, an upwardly-inclined hinged top at the receiving end, another portion of the chute being open at the top, means for yieldingly opposing upward swinging movement of said hinged top, and means for limiting downward movement thereof.

4. A chute for transferring bagasse between spaced sugar mills, said chute having side walls and an upwardly-inclined bottom at its receiving end and a downwardly-inclined bottom at its delivery end, a hinged top at the receiving end, means for limiting the extent of the downward swinging movement of said top, and separate, adjustable means for yieldingly opposing upward swinging movement thereof, the extent of such opposition being subject to selective variation by adjustment of said opposing means.

5. In an inclined intermediate bagasse carrier between the delivering and receiving rolls of spaced sugar mills, means forming a delivery chute of substantially uniform cross

sectional area adjacent the delivering rolls, and yielding means permitting enlargement of the chute under abnormal pressure.

6. In an inclined intermediate bagasse carrier between the delivering and receiving rolls of spaced sugar mills, a delivery chute extending from the delivering rolls into the carrier, and having a substantially uniform cross sectional area, a hinged wall for the chute and means for yieldingly permitting displacement of said wall under abnormal pressure.

7. In an inclined intermediate bagasse carrier between the delivering and receiving rolls of spaced sugar mills, a delivery chute extending from the delivering rolls into the carrier, and having a substantially uniform cross sectional area, a movable wall for the chute, a pivoted support for the wall adja-

cent the rolls, and a yielding support for the other end of the wall.

8. In an inclined intermediate bagasse carrier between the delivering and receiving rolls of spaced sugar mills a delivery chute associated with the delivery rolls and extending into the carrier, upper and lower walls for the chute, a pivotal support for the upper wall and adjacent the delivering rolls permitting its outer end to swing downwardly, means for limiting downward swinging movement of the outer end to normally maintain a uniform cross sectional area of the chute, and yielding means permitting upward swinging of said end under abnormal pressure.

In testimony whereof I affix my signature.

OTTO FRANKE.
